ELECTRICAL COMPONENT

Frederick F. Sylvester, Springfield, N. J.

Application April 1, 1946, Serial No. 658,618

12 Claims. (Cl. 171—327)

1

Simultaneous selection of piezoelectric crystals and adjustment of tuning element in electronic equipment is well known in the prior art as represented by the U. S. patents to Trogner, 1,609,744, dated December 7, 1926; Trogner, 1,727,575, dated September 10, 1929; Prochnow, 2,182,352, dated December 5, 1939; and Chandler, 2,382,203, dated August 14, 1945. With systems of these types, replacement of one or more crystals necessitates changes in the tuning element or its controls, an operation requiring the services of skilled technicians.

The prior art also teaches the use of a plurality of piezoelectric crystals, each provided with one or more separate and adjustable capacitors, wherein the capacitors are capable of being preset to resonate or tune a circuit comprising one or more coils, for selecting any one of a group of frequencies by manipulation of a particular push button or similar control.

It is likewise common practice to employ push button selection for tuning circuits incorporating a multiplicity of separate adjustable trimmer capacitors and fixed inductances where selector switches simultaneously switch two or more sets of trimmer capacitors to effect resonance at different frequencies with two or more inductance coils, as in a superheterodyne converter circuit. Most circuits of this general category employ two sets of trimmer capacitors and two coils, one set for the local oscillator circuit and one set for the antenna or radio frequency signal input circuit. There are also numerous modifications of such push-button converter circuits wherein piezoelectric crystals are not utilized, such as those employing a multiplicity of coils and a single fixed capacitor for each separate circuit with provision to adjust the inductance of each of the coils over a limited range for selection of a group of frequencies by push button switch selection of separate adjustable coils or adjustable capacitors.

Since the most carefully constructed trimmer capacitors and so-called slug-tuned coils (adjustable inductances), of the types in use with these prior art arrangements, are known to drift so appreciably over a period of time as to require repeated adjustment even in use with the broadcast frequencies (540 k. c. to 1600 k. c.), the problems attending the use of such agreements with frequency modulation and television frequency bands are even greater due to the presence of additional drift producing factors.

In accordance with the present invention these shortcomings of the prior art have been rem-

5 edied to a great extent by combining as a unit, a crystal or frequency determining element which controls the oscillator tuning, and a stable fixed capacitor having a predetermined value with respect to the crystal operating frequency for controlling various related circuits.

The broad combination of a piezoelectric crystal and capacitor constructed as a unit, is of course known, as exemplified by the U. S. patents to Tripp, 2,069,633, dated February 2, 1937; Fair, 2,260,707, dated October 28, 1941; and Usselman, 2,284,545, dated May 26, 1942. In each of these disclosures however, the relationships, both physical and electrical, between the crystals and capacitors are vastly different from those of the invention proposed herein, and therefore do not lend themselves to the same uses as contemplated by this invention.

Inasmuch as the inductance values of antenna 20 and loop coils for broadcast receivers, as well as the tuning inductance range or curve of oscillators have been more or less standardized among the various manufacturers, this invention adapts itself quite readily to a mode of distribution of broadcast receivers, for example, where the equipment would be manufactured and equipped with all components except the crystal-capacitor units, which would be installed by local dealers in accordance with the frequencies required in their 25 areas. Since the units are preferably assembled in cans or envelopes provided with projecting pins, it is merely necessary to press the pins into complementary sockets in much the manner that a vacuum tube is now installed. The provision of 30 suitable gang switches in the equipment permits the accurate selection of a desired broadcast frequency by actuation of a single control element, which simultaneously interconnects the crystal and capacitor of a unit in proper relationship 35 with their respective circuits.

The tuning unit contemplated may comprise a piezoelectric element of desired type and a capacitor having a predetermined value based upon the operating frequency of the crystal mounted 40 in a container through which suitable leads are extended for interconnection of the crystal and capacitor electrodes in the circuits for which they are designed. The piezoelectric element or crystal and capacitor are preferably arranged in non-inductive relationship and the container is preferably shielded or composed of shielding material.

Being generally desirable to effect electrical grounding of the container or envelope of the tuning unit, provision may be made to electrically 45 connect any of the base pins serving as terminals

for the elements within the container and the envelope itself; and in cases where the crystal or capacitor elements cannot be operated at ground potential due to particular circuit requirements, a separate base pin may be provided for electrically connecting the outer shell and any shielding means required within the tuning unit.

In some cases it may be desirable that the piezoelectric element be shielded or electrically isolated from the capacitor, electrostatically or electromagnetically or both. In cases where an electrode of either the crystal element or the capacitor element or an electrode of each are at ground potential, the grounded electrode (or electrodes) is preferably that adjacent to the other element, so as to provide a grounded shield between the two elements and their circuits. Where neither the crystal nor capacitor elements has an electrode at electrical ground potential, a metallic shield may be introduced between them in conductive relationship with the envelope.

The capacitor and crystal of each unit will have definitely computed values, depending upon the application for which the unit is intended. Some of the relationships computed include: a capacity inversely proportional to the square of the algebraic sum of the crystal operating frequency and a constant; a capacity inversely proportional to the square of the algebraic sum of the crystal operating frequency and another frequency; a capacity inversely proportional to the square of the crystal operating frequency modified by a constant; a capacity inversely proportional to the square of the crystal operating frequency modified by another frequency; and a capacity inversely proportional to the square of the crystal operating frequency.

The applications of the crystal and capacitor incorporated in a single plug-in unit, in accordance with present invention, will be manifold; as contemplated herein, the frequency of the piezoelectric element and the value of the fixed capacitor have a definite mathematical relationship with respect to one another for any given installation; and in each such installation, the substitution of a piezoelectric element of predetermined oscillation frequency requires a capacitor having predetermined characteristics to be associated with the related oscillating, frequency multiplying and/or amplifying circuits.

A more complete understanding of the invention will follow from a description of the attached drawing wherein:

Fig. 1 is a plan of a crystal-capacitor unit taken along line 1—1 of Fig. 2;

Fig. 2 is an elevation of the unit, partially in section, taken along line 2—2 of Fig. 1;

Fig. 3 is an elevation, partially broken away, looking from the right of Fig. 2, with the envelope removed;

Fig. 4 is an elevation looking from the left of Fig. 2, with the envelope removed;

Figs. 5 to 10 are circuit diagrams depicting typical applications of the units to known types of circuits;

Fig. 11 is a circuit diagram incorporating a plurality of units and switching arrangements; and

Fig. 12 is another circuit diagram incorporating the new units and switches.

The unit 20 depicted in Figs. 1 to 4 comprises a base 22 of thermoplastic or thermosetting dielectric material into which a plurality of terminal pins are molded in interlocking and pressure-tight relationship. Two of the pins 24 are provided for connection with the crystal elec-

trodes, while the other two pins 26 are connected with the capacitor electrodes. Each pin is provided with an intermediate collar 28 serving to anchor it in the molded base. As clearly shown in Fig. 4, the base is stepped to define a shoulder 30 in the radial face of which is formed an annular groove or depression 32 to serve as a seat for a volumetric sealing gasket 34 of rubber-like properties, which is deformed from its original condition depicted in Fig. 3 to the approximate shape shown in Fig. 2 upon assembly of the unit. The lower surface of the base and its periphery are preferably joined by a fillet or groove 36 for co-operation with the envelope upon assembly.

Upon the upper portions of the terminal pins 24 and 26 resilient mounting clips 38 and 40 for the crystal 42 and capacitor 44, all respectively, are provided. Each of these clips is secured to its terminal pin by a welded or soldered joint to assure adequate physical and electrical connections for proper performance in operation.

The crystal 42 is shown as having opposed electrodes 46 and 48 evaporated or otherwise applied as electrically conducting coatings, the electrode 46 being shown in Fig. 3 as having a tab 50 extending over the upper left edge of the proximate face of the crystal and terminating at the base of the bevel on the remote face, for electrical connection with the upper portion of the left hand clip 38; the electrode 48 being shown as having a tab 52 extending over the upper edge of the remote face of the crystal and terminating at the base of the bevel on the proximate face, for electrical connection with the other of the clips 38. Each of the clips 38 is formed from wire to form a structure which is somewhat channel-shaped in elevation, Fig. 2, having a web 54, a pair of opposed reentrant flanges 56, and a loop 58 bent or twisted from the plane of the web to form a suitable number of turns for embracing the upper portions of the terminal pins 24, to which they are bonded electrically and mechanically by welding or solder 60.

The capacitor 44, also provided with opposed electrodes 62 and 64 which may be applied as electrically conducting coatings is received by the clips 40, each clip being in physical and electrical contact with one of the electrodes. The dielectric body 66 has its proximate electrode 64, as viewed in Fig. 4, discontinued at the lower left corner to avoid contact with the left hand clip 40. Similarly, the remote electrode 62 is applied to clear the lower right hand corner of the dielectric body, as indicated in broken lines, to avoid contact with the right hand clip 40. Thus the right hand clip, still referring to Fig. 4, engages the proximate electrode and the left hand clip the remote electrode, the contacts in each case being completed by a soldered or cemented joint 67.

Each of the capacitor clips 40 is formed from a single blank of resilient metal and comprises a split socket 68 for embracing its terminal pin 26 to which it is secured by solder or welding 70. The capacitor engaging elements include a bowed resilient leaf 72 and a substantially erect leaf 74, which define an outwardly divergent jaw to receive the capacitor.

With the parts thus assembled, the envelope 78, which is shielded or which is itself a shield, both electrostatic and electromagnetic, is applied to the base and secured thereto in pressure-tight relationship. The envelope may have a generally cylindrical or frusto-conical body 80, formed with a closed upper end 82 and an open lower end. Towards its open end, the envelope is enlarged to

define an outwardly directed shoulder 84 and a downwardly depending skirt 86. When the envelope is applied to the base, its shoulder 84 deforms the gasket 34 causing it to flow into the groove 32 to effect a seal, whereupon the lower edge 87 of the skirt 86 is rolled or crimped into locking relationship with the base at its fillet 36.

In order to maintain one or more of the crystal and/or capacitor electrodes at a common potential with the envelope and/or with one another, thin conductive metal strips 88 may be affixed to the terminal pin or pins involved, at a convenient point such as the soldered or welded joints between such pins and their clips. The lower ends 89 of such strips 88 will trail over the upper portion of the base and gasket, down along the periphery of the base. Then when the envelope is applied and crimped, electrical contact will be established between the envelope and the one or more strips. Adjacent electrodes of the crystal and capacitor have been depicted in Fig. 2 as interconnected with the envelope to maintain them at common potential, but it should be understood that certain applications of the unit may require other arrangements in this behalf, including omission of the grounding entirely. In applications of the unit where the envelope or shell 78 should be connected to electrical ground and where it is not desirable to ground any portion of the crystal or capacitor elements, an additional terminal pin 91 (Fig. 1) incorporated in the base 22 will serve to ground the envelope through a conductive metal strip 88 which may be affixed to the pin 91 by welding or soldering and to the envelope in the manner previously described.

In cases where it is necessary to electrically shield the crystal element from the capacitor and neither element is to be electrically connected to ground, a metallic shield or plate 93, is interposed between the crystal and capacitor to engage the inner wall of the shell or envelope 78, and be retained therein by a resilient forced fit established by compression of its bent fingers 95, against the inner wall of the envelope and located by means of suitable slots formed in the upper surface of the base 22 with which the lower edge of the shield registers during assembly of the envelope upon the base. Location of shield 93 in these slots causes it to assume a position in a plane substantially parallel with respect to the crystal 42 and capacitor 44, and substantially equidistant with respect thereto. Electrical connection of the shield to ground is thus effected through the fingers 95, envelope 78, connecting strip 88, and terminal pin 91.

A Miller oscillator embodying the crystal-capacitor units of the present invention is depicted in Fig. 5. Whereas only one such unit has been illustrated, the unit terminals have been drawn to indicate adjustable taps relating them to the remainder of the circuit, whereby the taps may be shifted simultaneously to connect with terminals of any number of such units having different constants. This circuit is representative of a type of crystal controlled oscillation generators, for which it is desired to establish the relationship between the operating frequency f_2 of the crystal 42 and the value C_1 of the capacitor 44.

Where f_2 is the operating frequency of the crystal unit; and f_3 is the output operating frequency of the tuned resonant oscillator circuit;

$$f_3 = nf_2$$

circuit inductance having a fixed value of A henries; and C_1 is the capacity of the capacitor 44. At resonance,

$$5 \quad 2\pi f_3 L = \frac{1}{2\pi f_3 C_1}$$

or

$$10 \quad C_1 = \frac{1}{4\pi^2 L} \cdot \frac{1}{f_3^2}$$

Substituting for

$$15 \quad \frac{1}{4\pi^2 L}$$

a constant K_1

$$C_1 = \frac{K_1}{f_3^2}$$

or in terms of f_2

$$20 \quad C_1 = \frac{K_1}{(nf_2)^2}$$

This relationship may be expressed as a capacity inversely proportional to the square of: the crystal operating frequency modified by a constant.

25 With regard to the Tri-tet oscillator shown in Fig. 6, it may be said to represent harmonic-generating crystal oscillators to which units 20 may be applied to advantage. Here again only one unit has been shown, but with terminals indicated as shiftable from one such unit to another to vary the frequency characteristics of the circuit.

Where f_2 is the resonant frequency of the

35 crystal 42, and f_3 the operating frequency of the tuned resonant circuit L , C_1 , assuming a high reactance of L^1 at such frequency, L^1 can be neglected in determining the value C_1 of the capacitor 44 in terms of f_2 .

$$40 \quad C_1 = \frac{K_1}{f_2^2}$$

as in the preceding case.

But in this circuit, in general f_3 is slightly 45 higher than f_2 by a value Δf sufficient to assure stability under varying load.

Hence, since L is constant for a given circuit, and K_1 is the same as in the previous case,

$$50 \quad C = \frac{K_1}{(f_2 + \Delta f)^2}$$

or the capacity is inversely proportional to the square of: the crystal operating frequency modified by another frequency.

55 Fig. 7 of the drawing illustrates the use of the unit of the present invention in tuning a single-ended converter tube in a superheterodyne receiver. Here again, the circuit connections with the unit are indicated as readily shiftable to other units of the same type for operation at other frequencies. In this case f_1 is the incoming R. F. carrier frequency, f_2 or f_2^1 the local oscillator operating frequency established by the crystal 42, and f_3 the intermediate frequency. 60 The antenna coil secondary or loop inductance L is assigned a constant value of A henries. 65 The values of f_2 and f_2^1 are selected to produce the relationships

$$70 \quad f_2^1 + f_3 = f_1$$

and

$$f_2 - f_3 = f_1$$

where n is an odd whole number. L is the plate 75 Now considering the resonant circuit containing

the inductance L and the capacitor 44 having a capacitance C_1 :

$$2\pi f_1 L = \frac{1}{2\pi f_1 C_1}$$

or

$$C_1 = \frac{1}{4\pi L f_1^2} = \frac{1}{4\pi^2 A} \cdot \frac{1}{f_1^2}$$

Since

$$\frac{1}{4\pi^2 A}$$

is constant, it may be represented by K_1 whereupon

$$C_1 = \frac{K_1}{f_1^2}$$

substituting for f_1

$$C_1 = \frac{K_1}{(f_2 - f_3)^2}$$

or

$$C_1 = \frac{K_1}{(f_2 + f_3)^2}$$

and since in a particular circuit f_3 is a constant, the capacitance C_1 can be said to be inversely proportional to the square of the algebraic sum of the crystal operating frequency and a constant.

A Colpitts oscillator adapted to employ any number of the units of the present invention is shown in Fig. 8 as connected with one such unit with shiftable leads which can be connected with other such units as desired. Where f_2 is the operating frequency of the crystal 42, and f_3 the operating frequency of the resonant circuit including the capacitor 44 whose capacitance is C_1 , and an inductance L having a fixed value of A henries, it may be assumed that

$$f_2 = f_3$$

At resonance, as in previously discussed examples,

$$C_1 = \frac{K_1}{f_3^2}$$

and since $f_2 = f_3$

$$C_1 = \frac{K_1}{f_2^2}$$

Hence, it may be said that the capacity is inversely proportional to the square of the crystal operating frequency.

In the Pierce oscillator depicted in Fig. 9, selection of desired units is again indicated. The value C_1 of the capacitance 44 must be smaller at higher frequencies because lower values of feedback coupling are required at higher frequencies. L is an inductance whose value is such that it will not resonate at the crystal frequency. Since it is desirable that the plate load be capacitive at the crystal operating frequency, it will follow that the value of C_1 will be dependent upon variable factors other than the crystal operating frequency. This example illustrates a situation in which the circuit design should be established prior to a computation of the crystal-capacitor relationship.

Applications of the present unit to any composite triode-pentode converter, such as the pentagrid converter, heptode converter, hexode converter, or octode converter, are represented by Fig. 10, where again, any desired number of

the new units may be selectively introduced into the circuits by appropriate switching from the terminals of the single unit indicated to corresponding terminals of other units having desired constants. The relationship of the value of capacitor 44, (C_1), and the frequency of crystal 42, (f_2) is analogous to that developed for the circuit illustrated in Fig. 7, namely, the capacitance is inversely proportional to the square of: the algebraic sum of the crystal operating frequency and a constant.

Fig. 11 illustrates the application of a plurality of the units to a superheterodyne receiver using a single-ended converter tube. The five units 20 and their corresponding gang switches 90, 92, 94, 96 and 98 are arranged for selectively introducing the units into the circuits for attaining a push-button tuning, which requires no adjustment either at the time of installation or subsequently. There is also provided a switch 100 whose depression will establish circuits for manually tuning the receiver, independently of the crystal-capacitor units. The switches are of a known commercial type wherein depression of any one button will eject any of the others which may have been depressed previously. Such a receiver will be adapted for push-button tuning of a predetermined group of transmitted frequencies (five in the case illustrated) by introducing the terminal pins of units corresponding to such frequencies into sockets, such as those produced for use with miniature tubes, with reference to which, the numbers 1, 3, 5 and 7 have been applied to the uppermost unit of Fig. 11.

Fig. 12 represents a similar circuit utilizing six units of the present invention cooperating with six gang switches adapted for tuning six predetermined frequencies by the actuation of push buttons in the manner described with reference to Fig. 11. In this arrangement, there is no provision of manual tuning; the sixth switch 102 having been substituted for the manual tuning switch 100 of Fig. 11.

The arrangements illustrated in Figs. 11 and 12 will readily adapt themselves to an entirely new mode of distribution of radio receivers. The manufacturer can ship the receivers without the tuning units to any distributor regardless of geographical location. The distributor will maintain a stock of the units of the present invention suited to the needs of his particular area. Then to adapt the receiver to the broadcast frequencies desired by a given customer, the distributor need only insert the appropriate units corresponding to the desired frequencies without need for adjusting any components then or in the future.

No effort has been made to exhaust the various applications of the invention in describing the few illustrative examples in the foregoing description. Accordingly, these examples should not be construed as limiting the invention beyond the scope of the appended claims.

I claim:

1. A tuning unit comprising a piezoelectric element and a fixed capacitor having a predetermined value based upon the operating frequency of the element, mounted in substantially non-inductive relationship in a closed container, and leads for said element and capacitor extending through said container.

2. A tuning unit comprising a piezoelectric element and a fixed capacitor having a predetermined value based upon the operating frequency of the element, mounted in substantially non-inductive relationship in a sealed container provid-

ing shielding, and leads for said element and capacitor extending through said container.

3. A tuning unit comprising a piezoelectric element and a fixed capacitor having a predetermined value based upon the operating frequency of the element, mounted in substantially non-inductive relationship in a closed shielding container, and leads for said element and capacitor extending through said container.

4. A tuning unit comprising a piezoelectric element and a fixed capacitor having a predetermined value based upon the operating frequency of the element, mounted in substantially non-inductive relationship in a closed container providing shielding, said element and capacitor having adjacent electrodes connected to said shielding, and leads for said element and capacitor extending through said container.

5. A tuning unit comprising a piezoelectric element and a fixed capacitor having a predetermined value based upon the operating frequency of the element, mounted in substantially non-inductive relationship in a closed container, means electrostatically shielding said element from said capacitor, and leads for said element and capacitor extending through said container.

6. A tuning unit comprising a piezoelectric element and a separate capacitor having a capacity inversely proportional to the square of the algebraic sum of the element operating frequency and a constant, mounted in a closed container, and leads for said element and capacitor extending through said container.

7. A tuning unit comprising a piezoelectric element and a separate capacitor having a capacity inversely proportional to the square of the algebraic sum of the element operating frequency and another frequency, mounted in a closed container, and leads for said element and capacitor extending through said container.

8. A tuning unit comprising a piezoelectric element and a separate capacitor having a capacity inversely proportional to the square of the element operating frequency modified by a constant, said element and capacitor being mounted in substantially non-inductive relationship in a closed container, and leads for said element and capacitor extending through said container.

9. A tuning unit comprising a piezoelectric element and a separate capacitor having a capacity inversely proportional to the square of: the element operating frequency modified by a pre-selected frequency; said element and capacitor being mounted in a closed container, and leads for said element and capacitor extending through said container.

10. A tuning unit comprising a piezoelectric element and a separate capacitor having a capacity inversely proportional to the square of the element operating frequency, said element and capacitor being mounted in substantially non-inductive relationship in a closed container, and leads for said element and capacitor extending through said container.

11. A control system for oscillator circuits comprising matched piezoelectric element-capacitor units corresponding to predetermined frequencies, the capacitor of each unit having a predetermined value based upon the operating frequency of its element, each of said elements and capacitors of a unit being mounted in substantially non-inductive relationship in a closed container, leads for each of said elements and capacitors extending through its container, and means for selectively interconnecting said units in said circuits.

12. A control system for oscillator circuits comprising matched piezoelectric element-capacitor units corresponding to predetermined frequencies of different values, the capacitor of each unit having a predetermined value based upon the operating frequency of its associated element, leads for each of said elements and capacitors, and means for selectively interconnecting said units in said circuits.
